(57) **CLAIM**

The ornamental design of a blower nozzle, as shown and described.

DESCRIPTION

FIG. 1 is a right, rear, perspective view of a blower nozzle; FIG. 2 is a right-side view thereof;

FIG. 3 is a left-side view thereof;

FIG. 4 is a rear view thereof;

FIG. 5 is a front view thereof;

FIG. 6 is a top view thereof; and,

FIG. 7 is a bottom view thereof.

The broken lines illustrate environmental structure, and form no part of the claimed design.
